(57) **ABSTRACT**

A *Chrysanthemum* plant named 'Zanmudove Yellow' characterized by its medium sized blooms with light yellow ray florets and prolific branching; natural season flowering date October 1 (week 40); blooming for a period of 5 weeks.

2 Drawing Sheets

1

Botanical designation: *Chrysanthemum x morifolium* Ramat.

Cultivar denomination: "Zanmudove Yellow".

RELATED CULTIVARS

The new plant is a flower color mutant of 'Zanmudove' (U.S. Plant Pat. No. 24,618)

BACKGROUND OF THE INVENTION

The present invention relates to a new and distinct cultivar of *Chrysanthemum* plant, botanically known as *Chrysanthemum x morifolium* Ramat., commercially known as a garden mum, and hereinafter referred to by the cultivar denomination 'Zanmudove Yellow'. 'Zanmudove Yellow' is a product of a breeding and selection program which had the objective of finding flower color mutants from existing parent plants. The new plant comprises a whole plant mutant of the parent *Chrysanthemum* named 'Zanmudove'. Plants from the new cultivar 'Zanmudove Yellow' differ from plants of the parent in the color of the ray-florets. The ray-florets of the parent are white, while those of the new plant are yellow.

The new plant was discovered as a natural flower color mutant in October 2016 by Sjoukje Heimovaara. The first act of asexual reproduction of 'Zanmudove Yellow' was accomplished when after planting of the new variety as a motherplant in November 2016, vegetative cuttings from this motherplant were taken and propagated further in Rijsenhout, the Netherlands. In summer, about 6-8 days are needed to initiate roots in cuttings of the new cultivar, after another 5 days rooted plants are formed. The new cultivar has been found to retain its distinctive characteristics through successive propagations.

BRIEF DESCRIPTION OF THE DRAWINGS

The present invention of a new and distinct variety of *Chrysanthemum* (of about 21 weeks) is shown in the accom-

2

panying drawings, the color being as nearly true as possible with color photographs of this type.

FIG. 1 shows a plant of the new cultivar in full bloom.

FIG. 2 shows the various stages of blooms of the new cultivar.

FIG. 3 shows the various stages of foliage of the new cultivar.

DESCRIPTION OF THE INVENTION

10 The observations and measurements were gathered from plants in the period of 19 to 25 weeks of age grown outdoors in Rijsenhout, the Netherlands, under natural day length and temperature and planted in week 21 in 2018. The natural 15 blooming date of this crop was October 1 (week 40). The average height of the plants was 28 cm. No growth retardants were used. No tests were done on disease or insect 20 resistance or susceptibility. No tests were done on cold or drought resistance. This new variety produces medium sized 25 blooms with light yellow ray florets blooming for a period of five weeks. From the cultivars known to the inventor the most similar existing cultivar in comparison to 'Zanmudove Yellow' is 'Zanmuday' (U.S. Plant Pat. No. 24,670). When 30 'Zanmuday' and 'Zanmudove Yellow' are compared the following differences are noticed: Ray-florets of Zanmuday' are white, while those of 'Zanmudove Yellow' are light yellow.

35 The following is a description of the plant and characteristics that distinguish 'Zanmudove Yellow' as a new and distinct variety.

The color designations are taken from the plant itself. Accordingly, any discrepancies between the color designations and the colors depicted in the photographs are due to photographic tolerances. The color chart used in this 35 description is: The Royal Horticultural Society Colour chart, edition 2001.

Botanical Description of *Chrysanthemum x morifolium* Ramat. 'Zanmudove Yellow'

Bud:		Receptacle:
Size.—Small; cross-section 6 mm, height 4 mm.		Color.—Yellow-green 145D.
Shape.—Round.		Shape.—Domed raised.
Texture.—Pubescent.		Height.—3 mm.
Outside color.—Greyed-green 191A.		Diameter.—3 mm.
Phyllaries:		Reproductive organs:
Number.—24, arranged in 3 rows.		Androecium.—Present on only disc florets.
Shape.—Elliptic.		Stamen length.—3 mm.
Apex.—Acute.		Stamen color.—Yellow-green 144A.
Base.—Truncate.	10	Anther color.—Yellow 2A.
Margin.—Entire.		Pollen.—Present in a moderate amount.
Color.—Upper side: Green 138A. Lower side: Green 135B.		Pollen color.—Yellow 13A.
Length and width.—3-5 mm; 1.5 mm.	15	Gynoecium.—Present on both ray and disc florets.
Texture.—Pubescent.		Style color.—Yellow-green 154C.
Inflorescences:		Style length.—4 mm.
Type.—Double.		Stigma color.—Yellow 7A.
Height.—1.5 cm.		Stigma width.—1 mm.
Diameter.—4-5 cm.	20	Ovary.—Enclosed in calyx.
Peduncle length.—6-7 cm.		Ovary color.—Yellow-green 149D.
Peduncle color.—Greyed-green 194B.		Plant:
Peduncle diameter.—1-1.5 mm.		Type.—Bushy.
Peduncle texture.—Pubescent.		Growth habit.—Spherical shape.
Peduncle strength.—Not strong.	25	Growth rate.—Medium.
Number per branch.—About 6-8 inflorescences.		Height.—28 cm.
Duration of flowering.—5 weeks.		Width.—45-50 cm.
Seeds.—Produced in small quantities, ovate, Greyed-brown 199A, length 1.5 mm, diameter 0.5 mm; texture: rough with ribs.	30	Stem color.—Greyed-brown 199A.
Fragrance.—Faint <i>Chrysanthemum</i> odor.		Stem strength.—Medium strength.
Color inflorescences:		Stem brittleness.—Moderately brittle.
Center of inflorescence.—Immature stage: Yellow 7A; Mature stage: Yellow 13A.	35	Stem anthocyanin coloration.—Not observed.
Color of upper side of ray florets.—Yellow 8B.		Internode length.—2 cm.
Color of lower side of ray florets.—Yellow 8D.		Length of lateral branch.—From top to bottom 18-20 cm.
Tonality from distance.—A garden mum with yellow blooms.		Lateral branch color.—Green 138B.
Color of ray florets after aging of the plant.—Yellow 5D.	40	Lateral branch, attachment.—Weak.
Ray florets:		Lateral branch diameter.—2-2.5 mm.
Number of types.—One.		Lateral branch texture.—Pubescent with ribs.
Type.—Ligulate.		Branching (average number of lateral branches).—
Texture.—Upper and lower side smooth.	45	Prolific with 9 breaks after pinching.
Number.—180-190.		Natural season blooming date.—October 1 (week 40) in Rijshout, the Netherlands.
Shape.—Elliptic.		Root habits.—Fine, freely branching.
Apex.—Dentate to Rounded.		Root color.—White 155D.
Base.—Attenuate.		Rooting time.—6-8 days.
Cross-section.—Flat.	50	Formation rooted plants.—12-14 days.
Longitudinal axis.—Straight.		Foliage:
Length of corolla tube.—3 mm.		Leaf glossiness.—Upperside: Very weak. Lower side: Very weak.
Diameter corolla tube.—1 mm.		Leaf color.—Upper side: Green 137A. Lower side: Green 137B.
Ray floret margin.—Entire.		Color midvein.—Upper side: Yellow-green 147D. Lower side: Yellow-green 148D.
Ray floret length.—1.4-2.3 cm.	55	Size.—Small; length 2.6-5.5 cm, width 0.5-2.5 cm.
Ray-floret width.—2-5 mm.		Quantity (number per lateral branches).—25.
Ratio length/width.—High.		Shape.—Elliptic.
Disc florets:		Texture upper side.—Sparsely pubescent.
Disc diameter.—2 mm.	60	Texture under side.—Pubescent.
Number of disc florets.—5-10.		Venation arrangement.—Pinnate.
Shape.—Funnel shaped.		Shape of margin.—Serrated to Entire.
Color.—Yellow-green 145C at base to Green Yellow 11D at apex.		Shape of base of sinus between lateral lobes.—
Length.—4 mm.	65	Rounded.
Diameter.—0.8 mm.		

US PP31,669 P2

5

Margin of sinus between lateral lobes.—Diverging.*Shape of base.*—Attenuate.*Apex.*—Mucronulate.*Petiole attitude.*—Moderately upwards.*Petiole length.*—0.5-1 cm.*Petiole diameter.*—1-1.5 mm.*Petiole color.*—Yellow-green 147D.*Stipules.*—Small.

6

TABLE 1

Differences with the comparison variety, when grown under identical conditions			
5	Characteristic	'Zannuday'	'Zanmudove Yellow'
	Natural season blooming date	Week 41	Week 40
	Color upperside ray-florets	Yellow 12B	Yellow 8B

10 I claim:

1. A new and distinct *Chrysanthemum* plant named 'Zanmudove Yellow' as described and illustrated.
